[57] CLAIM

The ornamental design for a stroller cover, as shown and described.

DESCRIPTION

FIG. 1 is a top, front, right side perspective view of a stroller cover, showing my new design; the broken lines indicating a stroller handle and stroller wheels are shown illustrative purposes only;

FIG. 2 is an enlarged, right side elevational view thereof, the left side being a mirror image thereof;

FIG. 3 is an enlarged, front elevational view thereof;

FIG. 4 is an enlarged, top plan view thereof;

FIG. 5 is an enlarged, rear elevational view thereof;

FIG. 6 is an enlarged, bottom plan view thereof.
